Primary Examiner — Derrick Holland*Assistant Examiner* — Lauren Calve(74) *Attorney, Agent, or Firm* — Underwood & Associates, LLC(57) **CLAIM**

The ornamental design for a hanger adapter, as shown and described.

DESCRIPTION

FIG. 1 is a perspective view of a hanger adapter showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines shown represent unclaimed subject matter and form no part of the claimed design.
